UNITED STATES PATENT OFFICE.

JOHN A. BANSCHBACH, OF SHELBYVILLE, INDIANA.

AUTOMATIC TAPE-SEALING MACHINE.

1,273,128.

Specification of Letters Patent. Patented July 23, 1918.

Application filed March 27, 1917. Serial No. 157,735.

To all whom it may concern:

Be it known that I, JOHN A. BANSCHBACH, a citizen of the United States, residing at Shelbyville, in the county of Shelby and State of Indiana, have invented a new and useful Automatic Tape-Sealing Machine, of which the following is a specification.

The object of my invention is to provide a novel automatic tape sealing machine to seal packages, etc., with gummed tape; and to provide such a machine adapted to carry more than one roll of tape.

I attain the objects of my invention by the mechanism illustrated in the accompanying drawings, in which—

Figure 1 is a side elevation of my invention; Fig. 2 is a top plan of same; Fig. 3 is a vertical section; Fig. 4 is a front view; and Fig. 5 is a detail of a modified form 20 of the invention.

Similar numerals designate similar parts throughout the several views.

Referring to the accompanying drawings, I provide a suitable tape receptacle 1, having a cover 2, a rod 3 mounted on member 1 and carrying one or more (preferably two) tape rolls 4. These tape rolls may be of different width. I provide a suitable trough 5 containing water within which is revolvably mounted a moistening roll 6, carried by shaft 7. Secured to the end of shaft 7 is a pinion 8, meshing with a larger pinion 9, which in turn meshes with a relatively large gear wheel 10 mounted on shaft 11. Shaft 35 11 also carries, at its other end, a pinion 12, which meshes with gear 13, upon which tension is exerted by spring 14. A suitable tape guide roll 15 presses the strip of tape 4 against moistener roll 6, under the tension 40 of a suitable small spring 16, as shown in Fig. 3. Affixed to shaft 11 is a suitable cam wheel 17, with which a finger lever 18 is adapted to engage, lever 18 normally being held in engagement with cam wheel 17 by 45 means of a suitable spring 19. Tape guide roll 15 is mounted between suitable arms 20, which are slidably mounted on rod or shaft 21, as shown in Fig. 2.

Referring to Fig. 5, a modified form of 50 the invention as to certain details is illustrated. I provide a modified form of finger lever 22, corresponding in its function with lever 18; a spring 23 corresponding with spring 19 of the other form, and exerting 55 tension on the finger lever; and a pawl 24

suitably attached to lever 22 and adapted to actuate gear wheel 10. I may provide a plurality of pinions 9 intermediate of members 8 and 10, as illustrated in Fig. 5. A suitable spring 25 engages pawl 24. 60

In operation the finger is pressed on the button end of finger lever 18, thereby lifting its end out of engagement with cam 17. The shaft 11 in which cam 17 is mounted is thereby permitted to revolve, actuated by spring 65 14 causing a length of tape to be unrolled and passed over the moistening roll. The tape is then torn off against the sharp outer edge of the cover 2 over the moistening roll. Each time the same length of tape comes 70 forth when the finger lever is operated. Different sizes of cam wheels may, however, be supplied to vary the length of tape according to the requirements of the user. The coil spring may be wound up at infrequent intervals as required. This usually is about as often as an eight-day clock. The tape is moistened automatically as it unrolls. Just the required amount of moisture is obtainable by regulating the pressure exerted 75 by spring 16 on arms 20 which carry the tape guide or pressure roll 15. Roll 15 may be shifted to either side of the machine so as to operate either of the two rolls of tape with which the machine is ordinarily 80 supplied. When operating on one side, the tape on the other side does not unroll as no pressure is exerted on it. A change can very quickly be made on a narrow tape to a wide tape, or vice versa, according to the size of 85 the package to which it is to be applied. 90

It is within the contemplation of my invention to employ the modified form illustrated in Fig. 5. In this form of the invention a suitable pawl 24, pivoted to finger 95 lever 22, engages gear wheel 10 to actuate a series of pinions operatively connected with moistener roll 6. No spring 14 is employed in this form of the invention.

I may provide suitable thumb nuts 26 on 100 the end of shaft 3 to facilitate the adjustment of the tape rolls.

What I claim is:

1. In an automatic tape sealing machine, means to hold a plurality of rolls of tape, a 105 single laterally shiftable tape guide roll adapted to engage either of the tapes, a pressure roll, a moistener roll, a spring tensioned finger lever, geared mechanism operable by the finger lever, and arranged to rotate the 110

moistener roll to cause a strip of moistened tape to be discharged for use, substantially as shown.

2. A structure as specified in claim 1 in combination with a spring and gear mechanism actuated thereby to exert constant pressure to effect the automatic unwinding of the tape roll when the finger lever is depressed.

10 3. In a device of the class described, means for holding one or more rolls of tape com-

prising a casing having a hinged cover, a roll holding shaft having thumb nuts on its ends, a spring tension pressure roll mounted over a moistener, a trough adapted 15 to hold water, a moistener roll mounted in the trough over which the tape is unwound, means operatively connecting the moistener roll with a finger lever, and a spring tensioned finger lever adapted to intermittently 20 unroll the tape.

JOHN A. BANSCHBACH.
